[57] ABSTRACT

A rack (16) extends along a support column (12) for a work platform (10) which is guided for up and down movement along the support column (12). A pair of vertically spaced apart pinion wheels (56) engage the rack (16). Each pinion wheel (56) is mounted on its own pinion wheel support (32, 34). A separate extensible-retractable hydraulic cylinder (64, 68) is interconnected between each pinion wheel support (32, 34) and a frame portion (30, 88, 90) of the work platform (10). Each pinion wheel support (32, 34) includes an extendable-retractable lock element (100) having an end portion which when the lock element (100) is extended is in locking engagement with two portions of the pinion wheel (56). In use, the lock element (100) associated with one of the pinion wheels (56) is extending into locking engagement with tooth portions of its pinion wheel (56), to in that manner prevent rotation of the pinion wheel (56) and hold it in position relative to the guide member (12). At the same time the hydraulic cylinder (64, 68) which is connected to the support (32 or 34) for the first pinion wheel (56) is extended or retracted to raise or lower the work platform (10). At the same time the lock element (100) that is associated with the second pinion wheel (56) is retracted into an unlocked position, allowing its pinion wheel (56) to rotate along the rack (16) carried by the support column (12). The second cylinder (64, 68) is moved to a starting point so that at the end of the stroke of the first cylinder (64, 68) the second lock element (100) can be advanced to lock its pinion (26) in position and the first lock element (100) can be retracted to free its pinion wheel (26) for rotation along the rack (16), and the second cylinder (64, 68) can be operated to advance the work platform (10) and the first cylinder (64, 68) can be operated to return it to a start position.

ADVANCING MECHANISM AND SYSTEM
UTILIZING SAME FOR RAISING AND
LOWERING A WORK PLATFORM

DESCRIPTION

1. Technical Field

This invention relates to a mechanism for stepping a movable member in position along an elongated guide member. More particularly, it relates to such a mechanism which is adapted to provide an almost continuous step-by-step movement, and to a system in which a plurality of such mechanisms are used for raising and lowering a work platform relative to supporting columns.

2. Background Art

The general concept of a step-by-step advancing mechanism is quite old. However, a common problem with known systems is that the step-by-step movement is intermittent and slow. The jacking devices used for causing the movement are operated to cause an increment of movement. Then, such mechanisms must be repositioned while movement is stopped so that they can be used for affecting the next step or increment of movement.

The advancing mechanism of the present invention includes a pair of alternating mechanisms for making step advances. While one of the mechanisms is making a step advance, the other is repositioning itself so that substantially immediately following the step advance it can start making the next step advance. The advancing mechanism of the present invention is especially suitable for use in raising and lowering a platform relative to its support columns.

Mechanisms which exist in the patent literature for raising and lowering platforms relative to support columns are shown by the following U.S. Pat. Nos.: 2,841,961, granted July 8, 1958, to Joseph E. Lucas; 2,892,314, granted June 30, 1959, to John W. Hornsby et al; 2,920,870, granted Jan. 12, 1960, to George E. Suderow; 2,967,400, granted Jan. 10, 1961, to James I. Grant et al; 2,997,852, granted Aug. 29, 1961, to George E. Suderow; 3,028,143, granted Apr. 3, 1962, to David B. Cheskin; 3,082,607, granted Mar. 26, 1963, to John R. Sutton; 3,195,313, granted July 20, 1965, to Edwin P. Swatek; 3,605,669, granted Sept. 20, 1971, to Tsi Van Yu; 3,772,863, granted Mar. 27, 1973, to Isamu Itoh et al; 3,797,256, granted Mar. 19, 1974, to Robert P. Giblon; 3,804,369, granted Apr. 16, 1974, to John R. Sutton; 3,967,458, granted July 6, 1976, to Ralph E. Scales; 3,986,368, granted Oct. 19, 1976, to Clarence W. Livingston; 4,070,868, granted Jan. 31, 1978, to Franz Sedlmayer et al; 4,227,831, granted Oct. 14, 1980, to Darrel L. Evans; 4,225,069, granted Mar. 10, 1981, to Ralph D. Yielding; 4,265,568, granted May 5, 1981, to Robert P. Herrmann et al; 4,270,877, June 2, 1981, to Adrianus J. Post; 4,325,654, granted Apr. 20, 1982, to Milton Meckler; and 4,362,120, granted Dec. 7, 1982, to Cornelis Dekkers.

An advantage of mechanisms constructed according to the present invention is that the connection between the member being moved and the member along which it is being moved is made through a pinion carried by the movable member which is always in engagement with a rack carried by the fixed member. A lock element is moved into engagement with tooth portions of

the pinion, to in that manner lock the pinion against rotation, and hold it in position relative to the rack.

Brake mechanisms are known which include a lock element movable into engagement with tooth portions of a gear. Such a mechanism is shown by U.S. Pat. No. 449,843, granted Apr. 7, 1891, to George W. Blanchard; by U.S. Pat. No. 2,320,016, granted May 25, 1943, to Nelson Severinghaus; and by U.S. Pat. No. 3,043,403, granted July 10, 1962, to Oliver K. Kelley. This type of device is mentioned, but not as prior art, as such mechanism is from a nonanalogous art field.

DISCLOSURE OF THE INVENTION

The advancing mechanism of the present invention is 15 relatively simple in its structural makeup and is easy to operate and its use results in an almost continuous movement of the structure which is being moved by it.

In basic form, it comprises a pair of mechanisms, spaced apart along an elongated member. Each mechanism comprises at least one hydraulic cylinder having a first end which carries a pinion and a second end which is attached to a member which is to be moved relatively along the first member. A lock mechanism is associated with each pinion. Each lock mechanism is extendible into locking engagement with tooth portions of its pinion and is retractable into an unlocked position, freeing the pinion for rotation. The teeth of each pinion is always in meshing engagement with the teeth of a rack carried by the first member.

One of the cylinders is retracted or retracting and the other is extended or extending. In operation, one of the pinions is locked in position relative to the rack, and the cylinder attached thereto is operated for the purpose of moving a second member to which the opposite end of such cylinder is attached in position relative to the first member. At the same time, the other cylinder is used for repositioning its pinion, so that substantially immediately following the step of movement caused by the first cylinder, the second cylinder is ready to be used for 40 causing the next step.

In accordance with the invention, the first member may be fixed and the advancing mechanism of this invention used for moving the second member relative to it. Or, the second member may be fixed and the advancing mechanism of this invention may be used for moving the first member relative to the second member.

There are important constructional details and specific component arrangements which are also parts of the present invention. Also, a system utilizing the above 50 principles is a part of the invention. Such constructional details, component arrangements, and the system are described in the description of the best mode for carrying out the invention, and are particularly pointed out and distinctly claimed in the appended claims. Accordingly, the description of the best mode for carrying out the invention and the appended claims constitute portions of the disclosure of the invention.

BRIEF DESCRIPTION OF THE DRAWINGS

60 In the drawings, like reference numerals are used throughout the several figures, and:

FIG. 1 is a pictorial view, taken from above and looking towards one corner of a column supported platform, showing an advanced mechanism interconnected between each column and a related corner portion of the platform;

FIG. 2 is an elevational view of one of the advanced mechanisms, showing a lower set of cylinders ad-

vanced, an upper set of cylinders retracted, an upper pair of pinion wheels free to rotate along racks carried by the guide column, and a lower pair of pinions locked against rotation, and in a fixed position relative to the guide column, so that the upper pair of hydraulic wheels can be advanced for moving the upper pair of pinions in position relative to the guide column and the lower pair of hydraulic cylinders can be retracted for the purpose of lifting the platforms;

FIG. 3 is a view like FIG. 2, but at the end of the just described step of operation, and showing the upper pair of pinion wheels locked against rotation and the lower pair of pinion wheels unlocked, so that the lower pair of cylinders can now be used for moving the pair of pinions in position along the guide column while at the same time the upper pair of cylinders are being retracted for the purpose of lifting the platform an additional increment;

FIG. 4 is a cross sectional view taken substantially along line 4—4 of FIG. 2;

FIG. 5 is a cross sectional view taken substantially along line 4—4 of FIG. 2;

FIG. 6 is a cross sectional view taken substantially along line 6—6 of FIG. 2; and

FIG. 7 is an enlarged scale fragmentary view, with some parts in side elevational and some parts in longitudinal section, showing an embodiment of the extendible-retractable lock element which is associated with each pinion wheel.

BEST MODE FOR CARRYING OUT THE INVENTION

Referring to FIG. 1, an offshore work platform 10 is supported at its corners by a set of support columns 12. The platform 10 is vertically movable in position relative to the columns 12. Movement is achieved by operation of a set of four advance mechanisms, each one of which is interconnected between one of the corner portions of the platform 10 and the column 12 at such corner.

The advancing mechanism of the present invention is especially suited for use in raising and lowering a work platform in position relative to its support columns, and the system formed by combining the advancing mechanism with a work platform and its support columns is a very important aspect of the invention. However, the advancing mechanism has general utility and can be used for shifting many types of movable members in position relatively along many different types of elongated members.

The advancing mechanism concepts of the invention will now be described, in conjunction with the illustrated work platform raising and lowering system.

In the illustrated embodiment, the elongated guide member is a support column 12, which may be tubular in form. Preferably, each column 12 carries a pair of racks 16, occupying diametrically opposed positions on the column 12.

A support frame 18 is secured at its lower end 20 to a corner portion 22 of the platform 10. The frame 18 comprises a pair of upright side members 24, 26, an upper cross member 28 and an intermediate cross member 30. Frame 18 is an integral part of the platform or movable member 10.

The mechanism includes a pair of pinion wheel supports or yokes 32, 34, spaced apart along the column or guide member 12. In preferred form, each yoke 32, 34 includes a central portion 36 (FIGS. 4—6) which sur-

rounds the column 12 and a pair of side, pinion wheel mounting portions 38, 40. In like fashion, each cross member 28, 30 includes a central portion 42 which surrounds the column 12 and a pair of hydraulic cylinder anchoring side portions. In the case of cross member 30, the side portions 44, 46 serve as anchor points for a pair of hydraulic cylinders.

As best shown by FIG. 4, yoke end portions 38, 40 of yokes 32, 34 each includes a pair of spaced apart side cheeks 48, 50 or 52, 54. A pinion wheel 56 is positioned between the side cheeks 48, 50 and a pinion wheel 58 is positioned between the side cheeks 52, 54. The pinions 56, 58 are mounted for rotation by means of shafts 60, 62 which extend between and at their ends are carried by the cheeks 48, 50 and 52, 54, respectively.

The pinions 56, 58 have peripheral teeth which are always in engagement with the teeth of the racks 16.

In the illustrated embodiment, a separate pair of hydraulic cylinders is interconnected between each pinion wheel support 32, 34 and the movable structure. The cylinders associated with yoke 32 are designated 64, 66. The cylinders associated with yoke 34 are designated 68, 70. One end of each cylinder 64, 66, 68, 70 is secured to the movable structure and the opposite end is connected to a yoke structure 32, 34. In the illustrated embodiment, the barrel or chamber housing portions of the cylinders 64, 66, 68, 70 are pin connected at their lower ends to the movable structure. The opposite end of the cylinder 64, 66, 68, 70, which is the free end of the piston rod, makes a fixed connection to the yoke 32 or 34.

As best shown by FIG. 6, the lower end of each cylinder 68, 70 may include a mounting ear 72, 74 which is positioned between side plate portions 76, 78, and 80, 82 of the frame cross member 30. A pivot joint establishing pin 84 expands between members 76 and 80, and through an opening in the member 72. In similar fashion, a pivot joint establishing pin 86 extends between side members 80, 82, and through an opening in member 74. A similar arrangement exists at the lower ends of cylinders 64, 66, except that the side members are in the nature of side plates which project upwardly from the upper surface of platform 10. The foreground mounting plates are designated 88, 90 in FIGS. 2 and 3 and the pivot joint establishing pins are designated 92, 94.

As shown by FIG. 7, the upper end of each piston rod 96 may be thread connected to a mounting box portion 98 of its end of a yoke 32, 34. In accordance with an aspect of the invention, a lock mechanism is provided for each pinion 56, 58. The lock mechanism has a locked position in which it makes locking engagement with tooth portions of the pinion 56, 58, to in that manner prevent the pinion 56, 58 from rotating, and an unlocked position in which it is moved out from engagement with tooth portions of the pinions 56, 58. In the illustrated embodiment, the lock mechanism is in the form of an extendible-retractable element that is housed within housing 98. This element is designated 100 and it carries a plurality of teeth which are designed to engage teeth on the periphery of a pinion 56, 58. The lock element 100 may be positioned by means of a small fluid cylinder 102 (FIG. 7).

In operation, one pair 64, 66 or 68, 70 of the hydraulic cylinders 64, 66, 68, 70 is retracted and the other is extended. In FIG. 2 the cylinders 68, 70 are retracted and the cylinders 64, 66, are extended. If it is desired to move the movable platform or member 10 upwardly, the lock elements 100 associated with the lower pair of

pinions 56, 58 are extended for the purpose of locking the pinions 56, 58 in position relative to the column 12. The upper set of pinions 56, 58 are left unlocked. Then, the cylinders 64, 66 are retracted while at the same time the cylinders 68, 70 are extended. As cylinders 64, 66 5 retract, they pull the platform 10 upwardly relative to the anchored yokes 32. At the same time, the cylinders 68, 70 reposition the yoke 34 upwardly so that by the time the cylinders 64, 66 are fully retracted the cylinders 68, 70 are fully extended, and the step can be re- 10 peated, but with the cylinders 68, 70 being used this time to lift the platform 10 an additional increment. Immediately following forward traction of cylinders 64, 66 and full extension of cylinders 68, 70, the upper set of lock elements 100 are moved into position of locking engagement with the pinions 56, 58. Then, the lower set of lock elements 100 are retracted to unlock the lower pinions 56, 58. Then, the cylinders 68, 70 are retracted, for lifting the platform, and at the same time the cylinders 64, 66 are extended, for the purpose of reposition- 20 ing the yoke 32.

As will be easily appreciated, the process is reversible. That is, the platform can be moved downwardly by locking in position the pinions 56, 58 which are carried by the yoke that is connected to be retracted cylinders. Then, extension of the retracted cylinders will move the platform downwardly relative to the anchored yoke against which the cylinders are pushing as they extend. At the same time, the other set of cylinders are being retracted, for the purpose of repositioning the 30 yoke to which they are connected.

As will be appreciated, the advancing mechanism of the present invention provide an almost continuous raising or lowering of the platform 10. Essentially immediately at the end of the each increment of advancement the second assembly of cylinders is ready to commence another step of advancement. There is no waiting for a single advancement mechanism to be repositioned so it can be used for effecting the next step.

What is claimed is:

1. An advancing mechanism, comprising:
an elongated guide member, including at least one rack extending along a side thereof;
a movable member guided for movement along said guide member;
a pair of spaced apart pinion wheel supports, each carrying a pinion wheel which engages the rack, and each pinion wheel support including an extendible-retractable lock element having an end portion which when the lock element is extended is in locking engagement with tooth portions of the pinion wheel, and when retracted is out of engagement with tooth portions of the pinion wheel; and a separate extendible-retractable hydraulic cylinder innerconnected between each pinion wheel support and the movable member, 55
whereby the lock element associated with a first one of the pinion wheel supports can be extended into locking engagement with tooth portions of its pinion wheel, to in that manner prevent rotation of such pinion wheel and hold it in position relative to the guide member, while at the same time the hydraulic cylinder connected to the first pinion wheel support is extended or retracted to move the movable member in position relative to the first pinion wheel support and the guide member, and at the same time the lock element associated with the pinion wheel carried by the second pinion wheel 60
65

support is retracted into an unlocked position, allowing its pinion wheel to rotate along the rack carried by the guide member, and the second cylinder is moved to a starting position, so that at the end of the stroke of the first cylinder the second lock element can be advanced to lock its pinion wheel in position relative to the guide member, the first lock element can be retracted to free its pinion wheel from rotation along the rack carried by the guide member, and then the second cylinder can be operated to advance the movable member and the first cylinder can be returned to a start position.

2. An advanced mechanism according to claim 1, wherein the guide member includes a pair of racks, extending along opposite sides of the guide member, and each pinion wheel support includes a pair of pinion wheels, each in engagement with a different one of the racks, and a pair of extendible-retractable lock elements, one associated with each pinion.

3. An advanced mechanism according to claim 2, comprising a pair of extendible-retractable hydraulic cylinders innerconnected between each pinion wheel support and the movable member.

4. An advanced mechanism according to claim 1, 25 wherein each extendible-retractable lock element includes a two way fluid motor for moving the lock element between its extended and retracted position.

5. An advanced mechanism according to claim 1, wherein the thrust line of each hydraulic cylinder extends through the axis of rotation of a pinion wheel carried by the pinion wheel support to which the hydraulic cylinder is connected.

6. An advanced mechanism according to claim 1, wherein said movable member includes a base portion to which an end of the first hydraulic cylinder is connected and a frame portion projecting from said base portion along said guide member to a mounting portion for an end of the second hydraulic cylinder.

7. A work platform, comprising:
40 a platform member;
a plurality of support columns for the platform member; and a mechanism for raising and lowering the platform member, comprising:
45 at least one rack extending along a side of at least one support column;
a movable member guided for movement along said support column;
a pair of spaced apart pinion wheel supports, each carrying a pinion wheel which engages the rack, and each pinion wheel support including an extendible-retractable lock element having an end portion which when the lock element is extended is in locking engagement with tooth portions of the pinion gear, and when retracted is out of engagement with tooth portions of the pinion gear; and a separate extendible-retractable hydraulic cylinder innerconnected between each pinion wheel support and the movable member,

whereby the lock element associated with a first one of the pinion wheel supports may be extended into locking engagement with tooth portions of its pinion, to in that manner prevent rotation of such pinion and hold it in position relative to the support column, while at the same time the hydraulic cylinder which is connected to the first pinion wheel support is extended or retracted to move the movable member in position relative to the first pinion wheel support and the support column and at the

same time the lock element associated with the pinion wheel carried by the second pinion wheel support is retracted into an unlocked position, allowing its pinion wheel to rotate along the rack carried by the support column, and the second cylinder is moved to the same starting position as the first cylinder, so that at the end of the stroke of the first cylinder the second lock element can be advanced to lock its pinion in position relative to the support column, the first lock element can be retracted to free its pinion from rotation along the rack carried by the support column, the second cylinder can be operated to advance the movable member and the first cylinder can be operated to return it to a start position.

8. An advanced mechanism according to claim 7, wherein the support column includes a pair of racks, extending along opposite sides of the support column, and each pinion wheel support includes a pair of pinion wheels, each in engagement with a different one of the

racks, and a pair of extendible-retractable lock elements, one associated with each pinion.

9. An advanced mechanism according to claim 8, comprising a pair of extendible-retractable hydraulic cylinders innerconnected between each pinion wheel support and the movable member.

10. An advanced mechanism according to claim 7, wherein each extendible-retractable lock element includes a two way fluid motor for moving the lock element between its extended and retracted position.

11. An advanced mechanism according to claim 7, wherein the thrust line of each hydraulic cylinder extends through the axis of rotation of a pinion wheel carried by the pinion wheel support to which the hydraulic cylinder is connected.

12. An advanced mechanism according to claim 7, wherein said movable member includes a base portion to which an end of the first hydraulic cylinder is connected and a frame portion projecting from said base portion along said guide member to a mounting portion for an end of the second hydraulic cylinder.
